MAGNETIC PARTIAL SWITCHING CIRCUITS
John A. Kauffmann, Hyde Park, N.Y., assignor to International Business Machines Corporation, New York, N.Y., a corporation of New York
Filed Oct. 24, 1957, Ser. No. 692,131
24 Claims. (Cl. 340—174)

This invention relates to pulse transfer circuit and more particularly to circuits which are adapted to perform logical operations on binary digits.

Logical circuits are employed throughout accounting equipment and computers for widely different purposes and are variously known as gates, buffers, coincidence circuits and the like. This invention is directed to logical circuitry employing magnetic components operated in accordance with a novel mode which is hereafter termed "partial-switching".

To demonstrate how this "partial-switching" method may be employed, one embodiment of this invention is directed to a Two-Way AND logical circuit, which is a circuit having two input terminals and a single output terminal at which a pulse is produced when and only when a pulse is applied to both input terminals.

To further illustrate how the "partial-switching" method may be utilized another embodiment of this invention is directed to a Three-Way AND logical circuit, which is a circuit having three input terminals and a single output terminal at which a pulse is produced when and only when all three input terminals have a pulse applied to them.

A further embodiment of this invention is directed to a NEITHER NOR circuit as an additional illustration of how this "partial-switching" method may be employed, which circuit has two input terminals and a single output terminal at which a pulse is produced when and only when neither one nor both input terminals have a pulse applied to them.

Electronic computers employ a large number of vacuum tubes, and while such tubes may have long life individually, where large numbers are employed, the likelihood of failure of one tube is quite great. In many instances, the failure of only a single tube may completely disable the unit and as a consequence, there has been a trend, in computer research generally, to replace vacuum tube circuit with components which are more reliable, have longer life and are more economical.

Accordingly, an object of this invention is to provide a new and improved arrangement for switching circuits.

Another object of this invention is to provide a new and improved arrangement for logical circuits employing magnetic cores.

Yet another object of this invention is to provide new and improved AND circuits utilizing magnetic elements for performing the logical operations.

Still another object of this invention is to provide a new and improved NEITHER NOR circuit utilizing magnetic elements for performing the logical operation.

Another object of this invention is to provide logical circuits adapted to receive input pulses over a selectable time interval and to produce an output indication at a selectable time.

Other objects of the invention will be pointed out in the following description and claims and illustrated in the accompanying drawings, which disclose, by way of example, the principle of the invention and the best mode, which has been contemplated, of applying that principle.

In the drawings:

FIGURE 1 is a representation of the hysteresis characteristic obtained for a rectangular magnetic material of type employed.

2

FIGURE 2 is a circuit diagram of a magnetic core Two-Way AND circuit depicting one form of this invention.

5 FIGURE 3 is a circuit diagram of a magnetic core Three-Way AND circuit depicting another form of this invention.

FIGURE 4 is a circuit diagram of a magnetic core NEITHER NOR circuit depicting yet another form of this invention.

10 FIGURE 5 illustrates the relative timing of current pulses which are required for operating the circuits of FIGURES 2, 3 and 4.

Referring to FIGURE 1, the curve illustrated comprises a plot of flux density versus applied field for a magnetic core having a substantially rectangular hysteresis characteristic. The opposite remanence states are conventionally employed for representing binary information conditions and are arbitrarily designated as "0" and "1". With a "0" stored, a pulse applied to a winding linking the core in proper sense causes the loop to be traversed and the remanence state "1" is attained when the pulse terminates. Such a pulse is hereinafter referred to as a "write" pulse. Similarly, the core is read out or returned to the "0" state in determining what information has been restored by applying a pulse in the reverse sense to the same or another winding. Such a pulse is hereinafter referred to as a "read" pulse. Should a "1" have been stored, a large flux change occurs with the shift from "1" to "0" conditions with a corresponding voltage magnitude developed on an output winding. On the other hand, should a "0" have been stored, little flux change occurs and negligible signal is developed on the output winding.

For any given core, to obtain either the "1" or the "0" 35 limiting state, as described above, a given amount of flux change must occur within the core. Assume, however, that instead of a volt-time product applied to a given core which is sufficient to fully switch the core to one of the limiting states, only half this given amount is applied. Since only half the given amount of volt-time product is applied, only half the amount of flux change will occur within the core and subsequent to the application of such a signal, the core will attain a "mid-way", or "half-state", of residual flux density which is shown by "a" in the FIGURE 1. Similarly then, different increments of volt-time product applied will result in different residual states of flux density intermediate the "1" and "0" limiting states. Consider further, a circuit structure, wherein two cores, each having substantially the same characteristics and having windings with the same number of turns are connected in series. Assume a given volt-time product is applied which in itself is sufficient to fully switch any one of the two cores to a limiting state. This applied signal will then be shared by each of the cores and each core will then attain the "half-state" of residual flux density upon termination of such a signal. In each of the embodiments disclosed below the interconnection of two similar cores, as described, is the particular arrangement utilized to perform logical operations. It is understood however, that further cores may be similarly added to allow further subdivision, or sharing, of a given signal, or the amount of the signal may be varied to accomplish the logic desired.

65 A dot is shown adjacent one terminal of each of the windings illustrated in FIGURES 2, 3 and 4, indicating its winding direction. A write pulse is a positive pulse which is directed into the undotted end of the winding terminal which tends to store a "1," while a read pulse is a positive pulse directed into the dotted end of the winding terminal and tends to apply a negative magnetomotive force or store a "0."

The arrangements disclosed employ input and output coupling magnetic cores and inhibit cores arranged intermediate to so called storage magnetic cores which store certain logical information and these arrangements are adapted to be interconnected with each other and with similar type circuitry through such coupling cores.

The function and use of the so called "inhibit cores" is more fully disclosed and claimed in a copending application, Serial No. 689,827, filed October 14, 1957, now abandoned, by John A. Kauffmann and assigned to the same assignee.

The coupling cores and inhibit cores may be fabricated of ferrite materials like the storage cores; however, it is not essential that these cores exhibit the rectangular hysteresis characteristic required of the storage or memory cores as these devices function as variable impedance elements in controlling the transfer of information pulses, as will be more evident from the following description. As shown in the several figures, such interconnecting coupling cores and inhibit cores are illustrated in each of the subsequently described and depicted circuits which are labeled C_1 , C_2 , C_3 , C_4 , C_5 , I_1 , I_2 and I_3 for clarity. Also shown are two storage cores S_1 and S_2 which are adapted to store information received. The core S_1 is adapted to deliver the information received to another storage core S_3 of another logical component. The core S_2 is adapted to store information received and to act in conjunction with core S_1 to perform the logic subsequently described.

Referring to FIGURE 2, the core S_1 is provided with a winding 1 interconnected with an output winding 2 on the core C_2 , an output winding 3 on the core C_1 , an input winding 4 on the core C_3 through a diode D_1 and an output winding 5 on the core S_2 which interconnection is hereinafter referred to as loop A. Core C_3 is further provided with an output winding 6 which is interconnected with an input winding 8 on the core C_4 through a diode D_2 , wherein the core C_4 represents a further coupling core that may be coupled to the storage core S_3 through winding 7 series connected to the winding 6. This circuit is hereinafter referred to as loop B.

Storage cores S_1 and S_2 are adapted to receive information pulses transferred to them through the coupling cores C_1 and C_2 , which information is in turn transferred from the core S_1 , when the proper inputs are realized, through the coupling core C_3 to the following logical stage. The storage core S_3 is representative of a storage core in such following stage and thus receives information representing the logical function of Two-Way AND. Input signals are applied to the cores C_1 and C_2 by means of input windings designated 16 and 17, respectively. The coupling cores C_1 and C_2 are energized from a clock pulse source I_{RA} while the storage cores S_1 and S_2 along with coupling core C_3 are energized from a clock pulse source I_{RB} , with storage core S_1 further energized from a clock pulse source I_B and storage core S_3 energized from a clock pulse source I_A . A winding 9 is provided on the core C_1 and a winding 10 is provided on the core C_2 , which windings are series connected with the source I_{RA} . Similarly, a winding 12 on core S_1 , a winding 13 on core S_2 and a winding 14 on core C_3 are series connected with the source I_{RB} while a winding 11 on core S_1 is connected with the pulse source I_B on the core S_3 is connected with the pulse source I_A .

The sequence of pulses provided by the several clock pulse sources described above is indicated in FIGURE 5 and may be observed as being the same for each of the hereinafter described circuits with which such sources are adapted to operate.

To explain the operation of the circuits disclosed, consider first, in all circuits described, as an initial condition, that all of the cores shown are at a "0" state or at the lower remanence condition "0" shown in FIGURE 1.

Referring to FIGURE 2, with the initial condition as above described, let us consider its operation for the dif-

ferent conditions which may exist. Assume that at I_A clock pulse time, which is the interval during which input signals are applied to the circuit and designated input time as shown in FIGURE 5, no input is available to either core C_1 or C_2 . Since no input has been received, the flux conditions of the cores in loop A remain the same and a signal from the clock pulse source I_A is directed into the winding 15 on the core S_3 , which signal tends to read the core S_3 in the loop B. Since the core S_3 is already in the "0" state, negligible signal will be developed on the output winding 7 and the core remains in the "0" state. After the I_A clock pulse subsides the I_{RA} clock pulse source directs a signal into the windings 9 and 10 on the cores C_1 and C_2 , respectively, which tends to read both cores. Again, since both the cores C_1 and C_2 are already in the "0" state under the conditions assumed, no flux change occurs. The I_B clock pulse source next directs a signal into the winding 11 on the core S_1 , which signal tends to read this core. Again no appreciable flux change takes place since the core S_1 is already in the "0" state. Subsequent to the I_B clock pulse, the I_{RB} clock pulse source directs a signal into the windings 12, 13 and 14 on the cores S_1 , S_2 and C_3 , respectively, which current tends to read each of these cores. Again, no appreciable flux change takes place since these cores were initially in the "0" state. Under the condition that no information is transferred into the circuit, as described, no information is transferred out due to operation of the clock pulse source.

Assume an input signal is directed into the undotted end of the input winding 16 on the core C_1 . The core C_1 then switches from remanence condition "0" to the "1" state and in so doing induces a voltage on the output winding 3 such that the unmarked end is positive causing a counterclockwise current flow in loop A. This current flow is such as to read the core C_2 and write the cores S_1 , S_2 and C_3 . Since the core C_2 is already in the "0" remanence state negligible voltage drop appears across the winding 2. The windings 1 and 5 on cores S_1 and S_2 , respectively, are provided with an equal number of turns and have, in comparison, a greater number of turns than the winding 4 on the core C_3 . The current, thus, preferentially begins to switch both the cores S_1 and S_2 to the "1" state, but, since the core C_1 is supplying the volt-time product to switch each of the two cores, S_1 and S_2 , each of the cores switch only halfway towards the "1" state and attain a remanence state substantially midway between the "0" and "1" conditions or at point "a" as shown in FIGURE 1. At the conclusion of the input pulse, the core C_1 stands in the "1" remanence state while the cores S_1 and S_2 stand in the "half one" remanence state as shown by point "a," in FIGURE 1. Next, the I_{RA} clock pulse source directs a signal into the windings 9 and 10 on the cores C_1 and C_2 , respectively, which signal tends to read each of these cores. Since the core C_2 is already in the "0" state, it is unaffected, while the core C_1 , which was previously in the "1" state, is now reset to the "0" state engendering a flux change which induces a voltage on the winding 3 with the undotted end positive tending to cause a clockwise current flow in the loop A which is blocked and dissipated by the high back resistance of the diode D_1 . At the conclusion of the I_{RA} clock pulse, the I_B clock pulse source directs a signal into the winding 11 on the core S_1 which signal tends to read this core. Since the core S_1 was previously in "half one" remanence state, or at point "a" as shown on the hysteresis loop in FIGURE 1, the core is switched toward the "0" remanence condition inducing a voltage on the output winding 1 with the dotted end positive causing a counterclockwise current flow in the loop A which tends to write the cores S_2 and C_3 . Since the core S_2 is in the "half one" state and only a "half one" volt-time product is available from the core S_1 , this volt-time product is completely dissipated 75 in the preferential switching of the core S_2 from the

intermediate remanence condition to the "1" state. At the conclusion of the I_B clock pulse the I_{RB} clock pulse source subsequently directs a signal into the windings 12, 13 and 14 on the cores S_1 , S_2 and C_3 respectively, and is such as to read each of these cores. Since the cores S_1 and C_3 are already in the "0" state negligible flux change takes place. The core S_2 however, switches from the "1" to the "0" state causing a voltage to be induced on the output winding 5 with the undotted end positive causing a counterclockwise current flow in the loop A. This current tends to write the core C_3 , read cores C_1 and C_2 , and write the core S_1 . Since the cores C_1 and C_2 are already in the "0" state, they are unaffected, while the cores C_3 and S_1 are held in the "0" state by their I_{RB} drives. This leaves all cores in the "0" state and the circuit is ready for the next cycle of operation, the receipt of a single input having produced no output. It follows from the above, that a single input directed to the winding 17 on the core C_2 will have the same effect in that no output signal is produced to write the core S_3 .

Assume an input signal is now directed into the windings 16 and 17 on the cores C_1 and C_2 respectively, which signal is such as to write each of the cores. The core C_1 in switching from the "0" to the "1" state induces a voltage on the winding 3 with its undotted end positive causing a counterclockwise current flow in the loop A. The core C_2 in switching to the "1" state induces a voltage on the output winding 2 with the undotted end positive also causing a counterclockwise current flow in loop A. This counterclockwise current tends to write each of the cores S_1 , S_2 and C_3 . Again the cores S_1 and S_2 preferentially start switching from the "0" to the "1" state and since the volt-time product from both the cores C_1 and C_2 is now available, each of the cores S_1 and S_2 are completely switched to the "1" state. At the conclusion of the input signals, the cores C_1 , C_2 , S_1 and S_2 are left in the "1" remanence state, with the core C_3 in the "0" remanence state. Next, the I_{RA} clock pulse source directs a signal into the windings 9 and 10 on the cores C_1 and C_2 respectively, which signal tends to read each of the cores. The cores C_1 and C_2 are switched from the "1" to the "0" state and in so doing, a voltage is induced on the output windings 2 and 3 with the undotted end positive tending to cause current flow in a clockwise direction in the loop A. Current flow in this direction is blocked by the diode D_1 and the energy dissipated by its high back resistance. After the cores C_1 and C_2 have been fully reset to the "0" state by the I_{RA} clock pulse, the I_B clock pulse source now directs a signal into the dotted end of the winding 12 on the core S_1 which switches the core from the "1" to the "0" state and in so doing a voltage is induced on the winding 5 on the core S_1 with the dotted end positive, causing a counterclockwise current flow in the loop A. This current direction tends to write the cores S_2 and C_3 while at the same time tends to read the cores C_1 and C_2 . Since the cores C_1 and C_2 are already in the "0" state, negligible voltage drop appears on their windings 3 and 2, respectively. The core S_2 is already in the "1" state so here too there is experienced negligible voltage drop across the winding 5. The core C_3 , however, is switched from the "0" to the "1" state and in so doing, induces a voltage on the winding 6 with the undotted end positive so as to cause a counterclockwise current flow in loop B. This current direction tends to write both the cores S_3 and C_4 , however, because of the turns ratio, the core S_3 is switched to the "1" state in preference to the core C_4 . Thus, a transfer of information is accomplished only when both inputs are present. Further transfer from core S_3 is delivered through the core C_4 upon application of the next signal to the core S_3 by the I_A clock pulse source. After the information is stored in the core S_3 by the I_B clock pulse, the I_{RB} clock pulse resets the remaining cores of the circuit and it is prepared for further input signals. The I_{RB} clock

pulse source directs a signal into the windings 12, 13 and 14 to read each of the cores S_1 , S_2 and C_3 , respectively. The core S_1 is already in the "0" state, and therefore remains unaffected. The core S_2 is switched from the "1" to the "0" state and in so doing induces a voltage on the winding 5 with the dotted end positive tending to cause a counterclockwise current flow in the loop A. The core C_3 in switching from the "1" to the "0" state causes a voltage to be induced on the windings 4 and 6 with their dotted end positive causing a counterclockwise current flow in loop A, and a clockwise current flow in the loop B. The counterclockwise current flowing in the loop A tends to read each of the cores C_1 and C_2 while tending to write the core S_1 . Since the cores C_1 and C_2 are already in the "0" state, they are unaffected while the core S_1 is held in the "0" state by virtue of the I_{RB} drive. The clockwise current flow in the loop B is blocked and dissipated by the diode D_2 to leave all the cores in the "0" remanence state except the core S_3 , into which the information has been stored as described above.

The circuit disclosed above may be modified to avoid the need for the diodes D_1 and D_2 by replacing the diodes with resistors. This would necessitate the utilization of smaller, but longer, reset current clock pulses herein noted as the I_{RA} and I_{RB} clock pulses, as disclosed and claimed in a copending application Serial Number 528,594, filed August 16, 1955, now Patent No. 2,907,987, on behalf of Louis A. Russell, which application is assigned to the same assignee.

30 Referring to FIGURE 3, the circuit depicted in FIGURE 2, is modified by the addition of a coupling core C_5 and an inhibit core I_1 and functions as a Three-Way AND circuit. The core S_1 is provided with the winding 1 interconnected with the output winding 5 on the core S_2 , input winding 4 on the core C_3 , output winding 3 on the core C_1 through the diode D_1 , output winding 2 on the core C_2 , an output winding 18 on the core C_5 and an output winding 19 on the core I_1 which interconnection is hereinafter referred to as loop C. The output winding 6 on the core C_3 is interconnected in the same manner as above described for FIGURE 2 and is again referred to as loop B.

Similarly, the storage cores S_1 and S_2 are adapted to receive information pulses transferred to them through coupling cores C_1 , C_2 , and C_5 , which information in turn is transferred from the core S_1 , when the proper inputs are realized, through the coupling core C_3 to the following logical stage. The storage core S_3 is representative of a storage core in such following stage and thus receives information representing the logical function of Three-Way AND. Input signals are applied to the cores C_1 , C_2 and C_5 by means of the input winding 16, 17 and input winding 20, respectively. The coupling cores C_1 , C_2 , C_5 and I_1 are energized from the clock pulse source I_{RA} while the coupling cores C_3 and I_1 along with the storage cores S_1 and S_2 are energized from the clock pulse source I_{RB} . Storage core S_1 is further energized from the clock pulse source I_B along with coupling core I_1 . The storage core S_3 is energized from the clock source I_A along with the coupling core I_1 . A winding 21 is provided on the core C_5 and a winding 22 is provided on the core I_1 which windings along with the winding 9 on the core C_1 and the winding 10 on the core C_2 are series connected with the source I_{RA} . Similarly a winding 23 is provided on the core I_1 with the winding 12 on the core S_1 , the winding 13 on the core S_2 and the winding 14 on the core C_3 which windings are series connected with the clock pulse source I_{RB} . A winding 24 is provided on the core I_1 which winding is series connected to the winding 11 on the core S_1 and the clock pulse source I_B . A winding 25 is provided on the core I_1 , which winding is series connected to the winding 15 on the core S_3 and clock pulse source I_A .

75 Assume no input is available to the cores C_1 , C_2 or

C₅. Initially, the I_A clock pulse source directs a signal into the winding 25 on the core I₁ and the winding 15 on the core S₃. This signal tends to write the core I₁ and read the core S₃. Since S₃ is already in the "0" remanence state negligible flux change will occur, while the core I₁ will experience a large flux change in switching from the "0" to the "1" state. As a consequence of the flux change experienced in the core I₁, a voltage is developed on the output winding 19 such that the undotted end is positive tending to cause a clockwise current flow in loop C. This clockwise current flow is blocked and its energy is dissipated by the high back resistance of the diode D₁. At the conclusion of the I_A clock pulse, the I_{RA} clock pulse source directs a signal into the windings 9, 10, 21 and 22 on the cores C₁, C₂, C₅ and I₁, respectively, which signal tends to read each of these cores. The core I₁ switches from the "1" to the "0" state, while the cores C₁, C₂ and C₅ experience negligible flux change since they were previously in the "0" state. The core I₁ in switching from the "1" to the "0" state, induces a voltage on the output winding 19 with the dotted end positive causing a counterclockwise current flow in the loop C. This direction of current flow tends to write each of the cores S₁, S₂ and C₃. The current preferentially begins to switch the cores S₁ and S₂ to the "1" state, but since the core I₁ is supplying the volt-time product to switch each of the two cores S₁ and S₂, the cores switch only half way towards the "1" state. At the conclusion of the I_{RA} clock pulse, the core I₁ is left in the "0" remanence state while the cores S₁ and S₂ are left in the "half-one" remanence state shown by point "a" in FIGURE 1. Now, the I_B clock pulse source directs a signal into the windings 11 and 24 on the cores S₁ and I₁, respectively, which signal tends to read each of the cores S₁ and I₁. Since the core I₁ is already in the "0" state, negligible flux change occurs, while the core S₁ is switched from the "half-one" to the "0" state. Resetting the core S₁ to the "0" state causes a flux change which induces a voltage on the output winding 1 with the dotted end positive causing a counterclockwise current flow in the loop C which tends to write the core S₂ and the core C₃. Since the core S₂ was previously in the "half-one" state, and only a "half-one" volt-time product is available from core S₁ in switching to the "0" state, this volt-time product is completely dissipated in the preferential switching of the core S₂ to the "1" state. At the conclusion of the I_B clock pulse, the core S₁ is left in the "0" remanence state and the core S₂ is left in the "1" remanence state. The clock pulse source I_{RB} subsequently directs a signal into the windings 12, 13, 14 and a winding 23 on the cores S₁, S₂, C₃ and I₁ respectively, which signal is such as to read each of these cores. Since the core S₂ is the only core in the "1" state at this time, it alone switches to the "0" state to cause an appreciable flux change. This flux change induces a voltage on the output winding 1 with the dotted end positive which causes a counterclockwise current flow in the loop C which tends to write the cores C₃, I₁ and S₁, while tending to read the cores C₁, C₂ and C₅. The cores C₁, C₂ and C₅ are already in the "0" remanence state and the cores C₃, I₁ and S₁ remain in the "0" state due to the I_{RB} drive on their windings 14, 12 and 23, respectively. All cores are thus left in the "0" state and the circuit is ready for the next cycle of operation, no information has been transferred into the circuit, and, as described, no information is transferred out due to operation of the clock pulse sources.

Assume now an input signal is directed into the undotted end of winding 20 on the core C₅. The core C₅ then switches from remanence condition "0" to the "1" state and in so doing induces a voltage on the output winding 18 such that the undotted end is positive, while, at the same time, a voltage is developed across the output winding 19 on the core I₁ due to the operation of the I_A clock pulse source directing a write signal into the wind-

ing 25 on the core I₁ as described above. The voltage induced on the winding 19 on the core I₁ with the undotted end positive is equal and opposite to the voltage developed on the winding 18 on the core C₅ which voltages buck and effectively cancel to allow negligible current flow in loop C. After the I_A clock pulse subsides, the I_{RA} clock pulse source directs a signal into the windings 9, 10, 21 and 22 on the cores C₁, C₂, C₅ and I₁, respectively. This signal tends to read each of the cores C₁, C₂, C₅ and I₁ and reset them to the "0" state. Since the cores C₁ and C₂ are already in the "0" state they are unaffected, while the cores C₅ and I₁ experience a large flux change in switching from the "1" to the "0" state which change induces a voltage on the output windings 18 and 19 on the cores C₅ and I₁, respectively. The voltage induced on each of the windings 18 and 19 have their dotted end positive which buck and effectively cancel allowing negligible current flow in the loop C. At the termination of the I_{RA} clock pulse, all cores are left in their "0" remanence state. The I_B clock pulse source now directs a read signal into the windings 24 and 11 on the cores I₁ and S₁, respectively, and since both the cores I₁ and S₁ are already in the "0" state, they are unaffected and no transfer of information takes place. The I_{RB} clock pulse source subsequently directs a signal into the windings 23, 12, 13 and 14 on the cores I₁, S₁, S₂ and S₃, respectively, which tends to switch each of the cores toward the "0" state. Again, since all the cores are already in the "0" state, there is no appreciable flux change and no transfer of information takes place. No information has been transferred, as described above, due to the operation of the clock pulse sources, and all cores are left in the "0" state, thus, the circuit is ready for the next cycle of operation.

It follows from the above, that an input directed to the winding 16 on the core C₁, or the winding 17 on the core C₂ will have the same effect in that no output signal is produced to write the core S₃.

Assume an input is directed into the windings 17 and 20 on the cores C₂ and C₅, respectively. The cores C₂ and C₅ in switching from the "0" to the "1" state induce a voltage on their output windings 2 and 18 with the undotted end positive. This voltage is bucked by the core I₁ switching from the "0" to the "1" state, initiated by the operation of the I_A clock pulse source as previously described, inducing a voltage on the output winding 19 with the undotted end positive. The algebraic sum of the induced voltages is such that current flows in the counterclockwise direction in the loop C which current starts switching each of the cores S₁ and S₂ towards the "1" state. Effectively, there is only a volt-time product available from one core to switch each of the cores S₁ and S₂, therefore both cores switch only to the "half-one" state. At the termination of the I_A clock pulse, the cores C₂, C₅ and I₁ are left in their "1" remanence state, while the cores S₁ and S₂ are in their "half-one" remanence state. The clock pulse source I_{RA} now directs a read signal into the windings 9, 10, 21 and 22 on the cores C₁, C₂, C₅ and I₁, respectively. The core C₁ is already in the "0" state and is thus unaffected, while the cores C₂, C₅ and I₁ are each switched from the "1" to the "0" state to cause a flux change in each of the cores to induce a voltage on their output windings 2, 18 and 19, respectively, with their dotted end positive. The algebraic sum of these induced voltages is such that current tends to flow in the clockwise direction in the loop C. This current direction in loop C is blocked and its energy dissipated by the high back resistance of the diode D₁. At the termination of the I_{RA} clock pulse, the cores S₁ and S₂ are in their "half-one" remanence state, while all other cores are in the "0" remanence state. The clock pulse source I_B next applies a read signal into the windings 24 and 11 on the cores I₁ and S₁ respectively. Since the core I₁ is already in the "0" state, it is unaffected, while the core S₁ is

switched from the "half-one" state to the "0" state to cause a flux change which induces a voltage on the output winding 1 with the dotted end positive causing a counterclockwise current flow in the loop C which tends to write the cores S₂ and C₃. Again, since the core S₂ is in the "half-one" state and only a "half-one" volt-time product is available from the core S₁ in switching to the "0" state, the volt-time product is completely dissipated in the preferential switching of the core S₂ to the "1" state. At the conclusion of the I_B clock pulse, the core S₁ is in the "0" remanence state while the core S₂ is in the "1" remanence state. Subsequently, the clock pulse source I_{RB} directs a read signal into the windings 12, 13, 14 and 23 on the cores S₁, S₂, C₃ and I₁, respectively. Since the core S₂ is the only core in the "1" state at this time, it is switched from the "1" to the "0" state while the cores S₁, C₃ and I₁ are unaffected. The core S₂ in switching induces a voltage on the output winding 5 with the dotted end positive which causes a counterclockwise current flow in the loop C. This counterclockwise current flow tends to write each of the cores C₃, I₁ and S₁ while tending to read each of the cores C₁, C₂ and C₅. Since the cores C₁, C₂ and C₅ are already in the "0" state they are unaffected while the cores I₁, S₁ and C₃ are held in the "0" state by virtue of the I_{RB} drive; thus leaving all cores in the "0" state without the transfer of a signal to the core S₃ due to the clock pulse sources and readying the circuit for the next cycle of operation.

It follows from the above, that a write pulse directed to any two of the input windings 16, 17 and 20 on the cores C₁, C₂ and C₅ respectively, will have the same effect as described above, in that no output signal is produced to write the core C₃.

Assume now an input signal is directed into the input windings 16, 17 and 20 on the cores C₁, C₂ and C₅. Each of the cores will switch from the "0" to the "1" state to induce a voltage on each of the output windings 3, 2 and 18 on the cores C₁, C₂ and C₅, respectively, with their undotted ends positive. At the same time, a voltage is induced, due to the I_A clock pulse source directing a write signal into the winding 25 on the core I₁ as previously described, on the output winding 19 with the undotted end positive. The algebraic sum of the induced voltages is such that a counterclockwise current flows in the loop C. This counterclockwise current starts switching the cores S₁ and S₂, but now, since the effective volt-time product from two cores is available, each of the cores S₁ and S₂ are completely switched to the "1" state. At the termination of the I_A clock pulse, the cores C₁, C₂, C₅, I₁, S₁ and S₂ are left in the "1" remanence state, and the I_{RA} clock pulse source next directs a read signal into the windings 9, 10, 21 and 22 on the cores C₁, C₂, C₅ and I₁, respectively, which switches each of the cores from the "1" to the "0" state. As a result of the switching, a voltage is induced on each of the output windings 3, 2, 18 and 19 on the cores C₁, C₂, C₅ and I₁, respectively, with their dotted end positive. The algebraic sum of the induced voltages is such as to tend to cause a clockwise current flow in the loop C which is blocked and its energy is dissipated by the high back resistance of the diode D₁. At the termination of the I_{RA} clock pulse, the cores C₁, C₂, C₅ and I₁ are left in the "0" remanence state while the cores S₁ and S₂ are left in the "1" remanence state. The I_B clock pulse source now directs a read signal into the windings 24 and 11 on the cores I₁ and S₁, respectively, which signal does not effect the core I₁ but switches the core S₁ from the "1" to the "0" state causing a flux change which induces a voltage on the output winding 1 with the dotted end positive causing a counterclockwise current flow in the loop C. This counterclockwise current flow tends to write the cores S₂, C₃ and I₁ and to read the cores C₁, C₂ and C₅. Since each of the cores C₁, C₂ and C₅ are in the "0" state, they are unaffected. The core S₂ is already in the "1" state, and negligible voltage drop appears across the winding

5, while the core I₁ is held in the "0" state by virtue of the I_B clock pulse drive. Since the counterclockwise current flow in the loop C is directed into the undotted end of the winding 4 on the core C₃, the core C₃ switches from the "0" to the "1" state causing a large flux change in the core which induces a voltage on the winding 6 with the undotted end positive. This induced voltage causes a counterclockwise current flow in the loop B which is directed into the undotted end of the winding 7 on the core S₃ and completely switches the core S₃ to the "1" state. At the conclusion of the I_B clock pulse, the cores S₂, C₃ and S₃ are left in the "1" remanence condition, while the core S₁ is left in the "0" remanence condition. Subsequently, the I_{RB} clock pulse source directs a read signal into the windings 23, 12, 13 and 14 on the cores I₁, S₁, S₂ and C₃, respectively, which switches the cores S₂ and C₃ from the "1" to the "0" state, while leaving the cores I₁ and S₁ unaffected since they are already in the "0" state. Switching the core S₂ from the "1" to the "0" state causes a flux change which induces a voltage on the output winding 5 with the dotted end positive. Switching the core C₃ from the "1" to the "0" state induces a voltage on the windings 4 and 6 with their dotted end positive. The algebraic sum of the induced voltages on windings 5 and 4 on the cores S₂ and C₃ is additive to cause a counterclockwise current flow in the loop C. This counterclockwise current flow tends to read the cores C₁, C₂ and C₅ while tending to write the cores I₁ and S₁. Since the cores C₁, C₂ and C₅ are already in the "0" state they are unaffected, while the cores I₁ and S₁ are held in the "0" state by virtue of the I_{RB} drive on their respective windings 23 and 12. The voltage induced on the winding 6 on the core C₃ tends to cause a clockwise current flow in the loop B which current is blocked and its energy dissipated by the high back resistance of the diode D₂. Thus a transfer of information is accomplished only when all three inputs are present, and the output from the core S₃ is delivered through the core C₄ upon the application of the next I_A clock pulse, while all the cores associated with loop C are left in the "0" state readying the circuit for the next cycle of operation.

Referring to FIGURE 4 the circuit illustrated is basically as depicted in FIGURE 2 with inclusion of a core I₂ and a core I₃ with their associated windings. A circuit is thereby provided which is adapted to perform the function of NEITHER NOR. The core S₁ is provided with the winding 1 interconnected with an output winding 17 and on the core I₃, an output winding 26 on the core I₂ the output winding 2 on the core C₂, the output winding 3 on the core C₁, the input winding 4 on the core C₃ through the diode D₁, and the output winding 5 on the core S₂ which interconnection is hereinafter referred to as loop E.

The coupling cores I₂ and I₃ along with the storage core S₃ are energized from the clock pulse source I_A, while the coupling cores C₁, C₂, I₂ and I₃ are energized from clock pulse source I_{RA}, with the coupling cores I₂ and I₃ along with the storage cores S₁ energized from the clock pulse source I_B, and the coupling cores I₂, I₃ and C₃ along with the storage cores S₁ and S₂ energized from the clock pulse source I_{RB}. The windings 28, 29 and 15 on the cores I₂, I₃ and S₃, respectively, are series connected with the source I_A, while the windings 9, 10, 30 and 31 on the cores C₁, C₂, I₂ and I₃ are series connected with the source I_{RA}. Similarly, the windings 11, 32 and 33 on the cores S₁, I₂ and I₃, respectively are series connected with the source I_B and the windings 12, 13, 14, 34 and 35 on the cores S₁, S₂, C₃, I₂ and I₃, respectively, are series connected with the source I_{RB}.

Assume, initially, that no input signal is available. Initially, a write signal from the clock pulse source I_A, is directed into the windings 28 and 29 on the cores I₁ and I₂, respectively, and a read pulse is directed into the winding 15 on the core S₃. As a consequence of the write

signal, the cores I_2 and I_3 switch from the "0" to the "1" state and in so doing induce a voltage on the output windings 26 and 27, respectively, with the undotted end positive, tending to cause a clockwise current flow in the loop E which is blocked and its energy dissipated by the high back resistance of the diode D_1 . The read signal does not effect the core S_3 since it is already in the "0" state, and therefore negligible flux change occurs in the core. At the termination of the I_A clock pulse, the I_{RA} clock pulse source directs a read signal into the windings 9, 10, 30 and 31 on the cores C_1 , C_2 , I_2 and I_3 , respectively, which signal leaves the cores C_1 and C_2 unaffected since they are already in the "0" state, but resets the cores I_2 and I_3 from the "1" to the "0" state and in so doing induces a voltage on the output windings 26 and 27 on the cores I_2 and I_3 , respectively, with the dotted end positive, causing a counterclockwise current flow in the loop E. This counterclockwise current flow tends to switch each of the cores S_1 and S_2 from the "0" to the "1" state and, because the volt-time product of two cores switching is available, both the cores S_1 and S_2 are fully switched to the "1" state. At the conclusion of the I_{RA} clock pulse, the cores I_2 and I_3 are left in the "0" remanence state while the cores S_1 and S_2 are left in the "1" remanence state. The clock pulse source I_B now directs a read signal into the windings 11, 32 and 33 on the cores S_1 , I_2 and I_3 , respectively. Since the cores I_2 and I_3 are already in the "0" state, they are unaffected, while the core S_1 does switch from the "1" to the "0" state and in so doing induces a voltage on the output winding 1 with the dotted end positive, which voltage causes a counterclockwise current flow in the loop E. This counterclockwise current flow tends to write the cores S_2 , C_3 , I_2 and I_3 while tending to read the cores C_1 and C_2 . Since each of the cores C_1 and C_2 are already in the "0" state and the cores I_2 and I_3 are held in the "0" state by virtue of the I_B drive, and the core S_3 is already in the "1" state; negligible voltage drop appears on the windings 3, 2, 26, 27 and 5, respectively, allowing the core C_3 to switch from the "0" to the "1" state. The core C_3 in switching induces a voltage on its output winding 6 with the undotted end positive, to cause a counterclockwise current flow in the loop B. This counterclockwise current flow is directed into the undotted end of the winding 7 on the core S_3 and fully switches the core S_3 from the "0" to the "1" state. At the termination of the I_B clock pulse, the core S_1 is left in the "0" state, while the cores S_2 , C_3 and S_3 are left in the "1" state. The clock pulse source I_{RB} subsequently operates to direct a read signal into the windings 34, 35, 12, 13 and 14 on the cores I_2 , I_3 , S_1 , S_2 and C_3 , respectively. Since the cores I_2 , I_3 and S_1 are already in the "0" state, they are unaffected. The cores S_2 and C_3 , however, are switched from the "1" to the "0" state which causes a large flux change to occur in each of the cores. This flux change induces a voltage on the windings 5, 4 and 6 on the cores S_2 and C_3 , respectively, with the dotted end positive, to cause a counterclockwise current flow in loop E, and tending to cause a clockwise current flow in loop B. The counterclockwise current flow in loop E tends to read the cores C_1 and C_2 while tending to write the cores I_2 , I_3 and S_1 . Since the cores C_1 and C_2 are already in the "0" state, they are unaffected, while the cores I_2 , I_3 and S_1 are held in the "0" state by virtue of the I_{RB} drive. The clockwise current flow in the loop B is blocked and its energy is dissipated by the high back resistance of the diode D_2 . Thus since neither one, nor both of the possible inputs were available the circuit delivered a signal to the core S_3 which signal is delivered through the core C_4 in the next cycle of operation when the I_A clock pulse is applied, and all the cores associated with loop E are left in the "0" remanence state readying the circuit for the next cycle of operation.

Assume an input signal is directed into the input winding 17 on the core C_2 . The core C_2 switches from the "0" to the "1" state and in so doing induces a voltage on

the output winding 2 with the undotted end positive, while, at the same time, as described in the previous example, the I_A clock pulse source directs a signal into the windings 28 and 29 on the core I_2 and I_3 , respectively, which switches the cores I_2 and I_3 from the "0" to the "1" state to induce a voltage on the output windings 26 and 27, respectively, with their undotted end positive. The algebraic sum of these induced voltages is such as to tend to cause a clockwise current flow in the loop E. This clockwise current flow is blocked and dissipated by the diode D_1 . At the termination of the I_A clock pulse, and the input pulse, the cores C_3 , I_2 and I_3 are left in the "1" remanence state. These cores are then cleared by the clock pulse source I_{RA} which directs a read signal into the windings 9, 10, 30 and 31 on the cores C_1 , C_2 , I_2 and I_3 , respectively, to switch each of the cores C_2 , I_2 and I_3 , from the "1" to the "0" state. The cores C_2 , I_2 and I_3 in switching from the "1" to the "0" state induce a voltage on the output windings 2, 26 and 27, respectively, with their dotted end positive. The algebraic sum of the induced voltages is such as to cause a counterclockwise current flow in the loop E which current is directed into the undotted end of the windings 1 and 5 on the storage cores S_1 and S_2 , respectively, which starts to switch each of these cores to the "1" state. However, since the algebraic sum of the volt-time product available is equal to that of one core switching, the storage cores S_1 and S_2 each switch to only the "half-one" state. At the termination of the I_{RA} clock pulse, the cores C_2 , I_2 and I_3 are left in the "0" remanence state, while the storage cores S_1 and S_2 are left in the "half-one" remanence state. The clock pulse source I_B now directs a read signal into the windings 32, 33 and 11 on the cores I_2 , I_3 and S_1 , respectively, which leaves the cores I_2 and I_3 unaffected since they are already in the "0" state, but switches the core S_1 from the "half-one" state toward the "0" state and in so doing induces a voltage on the output winding 1, with the dotted end positive causing a counterclockwise current flow in the loop E. This counterclockwise current flow tends to write the cores S_2 and C_3 , but, since the core S_2 is in only the "half-one" state, and only half the volt-time product is available from the core S_1 , this volt-time product is completely dissipated in preferential switching of the core S_2 to the "1" state. At the termination of the I_B clock pulse, all the cores are left in the "0" state except the storage cores S_2 which is left in the "1" remanence state. The subsequent clock pulse source I_{RB} directs a read signal into the windings 34, 35, 12, 13 and 14 on the cores I_2 , I_3 , S_1 , S_2 and C_3 , respectively, which signal effects only the core S_2 to switch from the "1" to the "0" state, and in so doing induce a voltage on the output winding 5 with the dotted end positive, causing a counterclockwise current flow in the loop E. This counterclockwise current flow is such as to write the cores C_3 , I_2 , I_3 and S_1 while tending to read the cores C_1 and C_2 . The cores C_1 and C_2 are unaffected since they are already in the "0" state, while the cores C_3 , I_2 , I_3 and S_1 are held in the "0" state by the I_{RB} drive. At the termination of the I_{RB} clock pulse all cores are left in the "0" state. Thus since there was an input available to the core C_2 , no signal was transferred to the storage core S_3 due to clock pulse sources, and the circuit is ready for the next cycle of operation.

It again follows, from the above described operation, that if an input were directed into the winding 16 on the core C_1 , the effect is the same, in that no output signal is produced to write the core S_3 .

Assume in the next operation, that an input is directed into the windings 16 and 17 on the cores C_1 and C_2 , respectively. As a result, the cores C_1 and C_2 switch from the "0" to the "1" state and in so doing induce a voltage on the output windings 3 and 2, respectively, with the undotted end positive. At the same time, as described above, the cores I_2 and I_3 are also switched from the "0" to the "1" state, due to the operation of the I_A clock pulse source. The cores I_2 and I_3 in switching to the "1" state

induce a voltage on the output windings 26 and 27, respectively, with the undotted end positive. The algebraic sum of the induced voltages is such as to effectively cancel each other and allow negligible current flow. At the conclusion of the input pulses and the I_A clock pulse, the cores C_1 , C_2 , I_2 and I_3 are left in the "1" remanence state. The I_{RB} clock pulse source then directs a read signal into the windings 9, 10, 30 and 31 on the cores C_1 , C_2 , I_2 and I_3 , respectively; which switches each of the cores from the "1" to the "0" state to induce a voltage on their output windings 3, 2, 26 and 27, respectively, with the dotted end positive. The algebraic sum of the induced voltages is such as to again effectively cancel and allow negligible current flow in the loop E. At the termination of the I_{RA} clock pulse the cores C_1 , C_2 , C_7 and C_8 are left in the "0" remanence state, and the I_B clock pulse source now directs a read signal into the windings 32, 33 and 11 on the cores I_2 , I_3 and S_1 , respectively, which has no effect since all the cores are already in the "0" state. Subsequently, the I_{RB} clock pulse source directs a read signal into the windings 34, 35, 12, 13 and 14 on the cores I_2 , I_3 , S_1 , S_2 and C_3 , respectively, which has no effect since again all cores are in the "0" state and again no transfer of energy takes place. Thus, the circuit has performed the logical function of NEITHER NOR.

In the interest of providing a complete disclosure details of one embodiment of the invention wherein ferrite cores are employed, component values and current magnitudes are given below, which, however, is to be understood to be in no way limiting in that other component values and current magnitudes may be employed with satisfactory operation.

With the clock pulse currents I_A and I_B delivering a constant current of 1.9 amperes, the windings 28 and 29 may comprise four turns, the windings 11, 15, 32 and 33 may comprise ten turns; and with the clock pulse currents I_{RA} and I_{RB} delivering 1.1 amperes, the windings 9, 10, 14, 30, 31, 34 and 35 may comprise five turns while the windings 12 and 13 may comprise ten turns. In the coupling circuits interconnecting the storage and coupling cores, the windings 1, 5 and 7 may comprise ten turns, the windings 4, 16, 17 and 18 may comprise five turns and the windings 2, 3, 6, 26 and 27 may comprise twelve turns, with the diodes D_1 and D_2 of low forward impedance having a sufficient recovery time such as an 1N 270 diode manufactured by the Transitron Company.

In this particular embodiment each of the clock pulse currents I_A , I_{RA} , I_B and I_{RB} may be a one microsecond pulse having a two-tenths microsecond rise time. Each of the S and C cores may comprise toroids of magnesium-manganese ferrite composition having an outside diameter of 0.100 inch, inside diameter of 0.070 inch and a thickness of 0.120 inch. This thickness may be obtained by stacking four cores each of 0.030 thickness and winding the stack as a single core unit.

While there have been shown and described and pointed out the fundamental novel features of the invention as applied to a preferred embodiment, it will be understood that various omissions and substitutions and changes in the form and details of the device illustrated and in its operation may be made by those skilled in the art without departing from the spirit of the invention. It is the intention therefore, to be limited only as indicated by the following claims.

What is claimed is:

1. A logical "and" circuit comprising a first and a second magnetic storage core each capable of attaining opposite zero and one representative states of residual magnetization and a state intermediate thereto; control winding means on each of said storage cores; a first, a second and a third coupling core; input and output winding means on each of said coupling cores; circuit means including a diode series connecting the output winding means on said first and second coupling cores, said control

70
75

winding means and said input winding means on said third coupling core; a first, a second and a third clock pulse source adapted to deliver a series of pulses displaced in time; winding means on said first and second coupling cores connected with said first clock pulse source and adapted to drive said first and second coupling cores toward a zero residual state when energized; winding means on said first storage core connected with said second clock pulse source and adapted to drive said first storage core toward the zero state when energized; winding means on said first and second storage cores and said third coupling core connected with said third clock pulse source adapted to drive said first and second storage cores and said third coupling core toward the zero state when energized.

2. A logical "and" circuit comprising a first and a second magnetic storage core each capable of attaining opposite datum and binary one representing states of residual magnetization and a partially switched state intermediate thereto, said cores being formed of material having a substantially rectangular hysteresis characteristic; control winding means on each of said storage cores; a first, a second and a third coupling core; input and output winding means on each of said coupling cores; circuit means including an asymmetrical impedance device connecting the output winding means on said first and second coupling cores, said control winding means and said input winding means on said third coupling core; shift winding means on said first coupling core connected in series with shift winding means on said second coupling core adapted to drive said first and said second coupling cores toward a datum residual state when energized from a first clock pulse source; shift winding means on said first storage core adapted to drive said first storage core toward the datum residual state when energized from a second clock pulse source; shift winding means on said first storage core series connected to shift winding means on said second storage core and shift winding means on said third coupling core adapted to drive said first and second storage cores and said third coupling core toward the datum residual state when energized from a third clock pulse source.

3. A circuit as described in claim 2 including means for energizing said shift winding means comprising said first, second and third clock pulse sources, said sources being actuated in sequence in the order named.

4. A logical "and" circuit comprising a plurality of magnetic storage cores each capable of attaining selective states of residual magnetization intermediate a first and a second limiting state of residual magnetization; a like plurality of input coupling cores; an output coupling core; control winding means on each of said storage cores; input and output winding means on each of said coupling cores; circuit means connecting the output winding means on said input coupling cores; said control winding means on each of said storage cores and the input winding means on said output coupling core; shift winding means on each of said input coupling cores adapted to be energized simultaneously and to drive said input coupling cores toward the first residual state; additional shift winding means on one of said storage cores adapted to drive said one of said storage cores toward the first residual state when energized; further shift winding means on each of said storage cores and said output coupling core adapted to be energized simultaneously and to drive said storage cores and said output coupling core toward the first residual state.

5. A logical "and" circuit comprising a first and a second magnetic storage core each capable of selectively attaining half states of residual magnetization intermediate zero and one representing residual states; control winding means on each of said storage cores; a first, a second, a third and a fourth coupling core; input and output winding means on each of said coupling cores; an in-

hibit core; output winding means on said inhibit core; circuit means including a diode series connecting the output winding means on said first, second and third coupling cores and said inhibit core, said control winding means on said first and second storage cores and said input winding means on said fourth coupling core; a first, a second, a third and a fourth clock pulse source adapted to deliver a series of pulses displaced in time; winding means on said first, second and third coupling cores and said inhibit core connected with said first clock pulse source and adapted to drive said first, second and third coupling cores and said inhibit core toward a zero residual state when energized; winding means on said inhibit core and said first storage core connected with said second clock pulse source and adapted to drive said inhibit coupling core and said first storage core toward the zero residual state when energized; winding means on said inhibit core, said first and second storage cores and said fourth coupling core connected with said third clock pulse source and adapted to drive said inhibit core, said first and second storage cores and said fourth coupling core toward the zero residual state when energized; winding means on said inhibit core connected with said fourth clock pulse source and adapted to drive said inhibit core to a one residual state when energized.

6. A logical "and" circuit comprising a first and a second magnetic storage core each formed of a magnetic material having a substantially rectangular hysteresis characteristic and capable of selective attainment of half states of residual magnetization intermediate first and second residual states; control winding means on each of said storage cores; a first, a second, a third and a fourth coupling core; input and output winding means on each of said coupling cores; an inhibit core; output winding means on said inhibit core; circuit means including an asymmetrical impedance device connecting the output winding means on said first, second and third coupling cores and said inhibit core, said control winding means on said first and second storage cores and said input winding means on said fourth coupling core; shift winding means on each of said first, second and third coupling cores series connected with shift winding means on said inhibit core adapted to drive said first, second and third coupling cores and said inhibit core toward a first residual state when energized from a first clock pulse source; shift winding means on said inhibit core series connected with shift winding means on said first storage core adapted to drive said inhibit core and said first storage core toward the first residual state when energized from a second clock pulse source; shift winding means on said inhibit core series connected with shift winding means on each of said first and second storage cores and shift winding means on said fourth coupling core adapted to drive said inhibit core, said first and second storage cores and said fourth coupling core toward the first residual state when energized from a third clock pulse source; shift winding means on said inhibit core adapted to drive said inhibit core toward a second residual state in a direction opposite to said first state when energized from a fourth clock pulse source.

7. A circuit as described in claim 6 including means for energizing said shift winding means comprising said first, second, third and fourth clock pulse sources wherein said sources are actuated in sequence in the order named.

8. A logical "and" circuit comprising a first and a second magnetic storage core each of said cores capable of selective attainment of states of residual magnetization intermediate a first and a second limiting state of residual magnetization; control winding means on each of said storage cores; a first, a second, a third and a fourth coupling core; input and output winding means on each of said coupling cores; an inhibit core; output winding means on said inhibit core; circuit means including an asymmetri-

cal impedance device coupling the output winding means on said first, second and third coupling cores and said inhibit core, said control winding means on said first and second storage cores and said input winding means on said fourth coupling core; shift winding means on each of said first, second and third coupling cores and said inhibit core adapted to be energized simultaneously and to drive said first, second and third coupling cores and said inhibit core toward the first residual state when energized; additional shift winding means on said inhibit core and shift winding means on said first storage core adapted to be energized simultaneously and to drive said inhibit core and said first storage core toward the first residual state when energized; further shift winding means on said inhibit core; on each of said storage cores and said fourth coupling core adapted to be energized simultaneously and to drive said inhibit core, each of said storage cores and said fourth coupling core toward the first residual state when energized; and shift winding means on said inhibit core adapted to drive said inhibit core toward the second residual state.

9. A logical "neither nor" circuit comprising a first and a second magnetic storage core each capable of selectively attaining half states of residual magnetization intermediate zero and one representing residual states; control winding means on each of said storage cores; a first, a second and a third coupling core; input and output winding means on each of said coupling cores; a first and a second inhibit core; output winding on each of said inhibit cores; circuit means including a diode series connecting the output winding means on each of said first and second coupling cores and said inhibit cores, said control winding means on each of said storage cores and said input winding means on said third coupling cores; a first, a second, a third and a fourth clock pulse source adapted to deliver a series of pulses displaced in time; winding means on said first and second coupling cores and said first and second inhibit cores connected with said first clock pulse source and adapted to drive said first and second coupling core and said first and second inhibit core toward a zero residual state when energized; winding means on said first and second inhibit cores and said first storage core connected with said second clock pulse source and adapted to drive said first and second inhibit cores and said first storage core toward the zero residual state when energized; winding means on said inhibit cores, said storage cores and said third coupling core connected with said third clock pulse source and adapted to drive said inhibit cores, said storage cores and said third coupling core toward the zero residual state when energized; winding means on said inhibit cores connected with said fourth clock pulse source and adapted to drive said inhibit cores toward a one residual state when energized.

10. A logical "neither nor" circuit comprising a first and a second magnetic storage core each of said cores made of material having a substantially rectangular hysteresis characteristic and capable of attaining half states of residual magnetization; intermediate first and second residual states; control winding means on each of said cores; a first, a second and a third coupling core; input and output winding means on each of said coupling cores; a first and a second inhibit core; output winding means on each of said inhibit cores; circuit means including an asymmetrical impedance device connecting the output winding means on said first and second coupling cores and said inhibit cores, said control winding means on said storage cores and said input winding means on said third coupling core; shift winding means on each of said first and second coupling cores series connected with shift winding means on each of said inhibit cores adapted to drive said first and second coupling cores and said inhibit cores toward a first residual state when energized from a first clock pulse source; shift winding means on each of said inhibit cores series connected with shift winding means on said first storage core adapted to drive said said first storage core adapted to drive said

inhibit cores and said first storage core toward the first residual state when energized from a second clock pulse source; shift winding means on each of said inhibit cores series connected with shift winding means on each of said storage cores and said third coupling core adapted to drive each of said inhibit cores, said storage cores and said third coupling core toward the first residual state when energized from a third clock pulse source; and shift winding means on said first inhibit core series connected with shift winding means on said second inhibit core adapted to drive said first and second inhibit cores toward a second residual state in a direction opposite from said first residual state when energized from a fourth clock pulse source.

11. A circuit as described in claim 10 including means for energizing said shift winding means comprising said first, second, third and fourth clock pulse sources wherein said sources are actuated in sequence in the order named.

12. A magnetic core circuit comprising a plurality of magnetic storage cores each capable of retaining selective states of residual magnetization intermediate a first and a second limiting state of residual magnetization; control winding means on each of said cores; a like plurality of inhibit cores; output windings on each of said inhibit cores; a like plurality of input coupling cores; an output coupling core; input and output winding means on each of said coupling cores; circuit means including an asymmetrical impedance device connecting the output winding means on said input coupling cores and said inhibit cores, said control winding means on each of said storage cores and said input winding means on said output coupling core; shift winding means on each of said input coupling cores and each of said inhibit cores adapted to be energized simultaneously and to drive said input coupling cores and said inhibit cores toward the first residual state; additional shift winding means on each of said inhibit cores and one of said storage cores adapted to be energized simultaneously and to drive said inhibit cores and said one of said storage cores toward the first residual state; further shift winding means on each of said inhibit cores and said storage cores and said output coupling core adapted to be energized simultaneously and to drive said inhibit cores, said storage cores and said output coupling core toward the first residual state; and shift winding means on each of said inhibit cores adapted to be energized simultaneously and to drive said inhibit cores toward the second residual state.

13. A logical information transfer circuit including a plurality of magnetic storage means each capable of attaining selective states of residual magnetization intermediate a first and a second limiting state; control means on each of said storage means; a plurality of input means; circuit means series connecting said control means and coupling said input means; signal means operably connected with said input means; pulse means connected with said storage means; said pulse means being operable to apply a first pulse to said storage means and establish said storage means in the first limiting residual state; said signal means thereafter being operable to selectively apply a signal to said input means and read in information by establishing said storage means in a selective residual state; said pulse means being operable to apply a second pulse to said storage means and establish said first storage means in the first limiting residual state and to produce an output in said control means indicative of the magnetization necessary to establish all of said storage means in said second limiting residual state.

14. A circuit as described in claim 13 wherein said storage means comprise magnetic storage cores.

15. An information controlling device including a first and a second magnetic storage core each capable of attaining selective half states of magnetization intermediate and including a zero and a one limiting state; each of said cores having a reset winding and a control winding thereon; circuit means including a signal means series con-

necting said control windings; means for selectively energizing said reset windings to establish said cores in the zero residual state; said signal means adapted to apply a signal to said control windings to read in a bit of information and selectively establish said cores in the intermediate and one limiting states; and means for resetting said first core to the zero residual state to produce an output in said control winding means the magnitude of which is indicative of the magnetization force necessary to establish both of said cores in the one residual state.

16. An information controlling device including a plurality of magnetic storage cores each capable of attaining selectively residual states of magnetization intermediate and including a first and a second limiting residual state; winding means on each of said cores; signal means operably connected with said winding means; said signal means comprising first means selectively applying a first signal to said winding means to simultaneously establish said cores in the first residual state; second means applying a second signal to said winding means to read in information by establishing each of said cores in a selective residual state, and third means applying a third signal to said winding means to reset at least one of said cores to the first residual state and produce an output in a series connected winding coupling each of said cores the magnitude of which is indicative of the magnetizing force necessary to establish all of said cores in the second residual state.

17. An information controlling device including a plurality of magnetic storage cores each of said cores capable of attaining selective residual states of magnetization intermediate and including a first and a second limiting residual state and formed of material having a substantially rectangular hysteresis characteristic; winding means on each of said cores; signal means operably connected with said winding means; said signal means comprising first means adapted to apply a first signal to said winding means to simultaneously establish each of said cores in the first limiting state, second means adapted to apply a second signal to further ones of said winding means to cause all of said cores to assume a selective residual state in representing said information, and third means adapted to apply a third signal to another one of said winding means on at least one of said storage cores to reset at least one of said storage cores to the first limiting state and produce an output in said winding means the magnitude of which is indicative of the magnetizing force necessary to establish all of said cores in the second limiting state.

18. In an information handling circuit, a first and a second magnetic core made of material exhibiting first and second limiting stable states of remanent flux density, winding means inductively coupled to said cores, means for energizing said winding means during a first and a second interval of time comprising, first means energizing said winding means during the first interval of time for establishing both said cores in a similar stable state of flux density intermediate said limiting states which conjointly defines said information, and second means energizing said winding means during said second interval of time for establishing said first core in said first limiting state and to read out said information.

19. In a circuit, a first and a second magnetic core each made of magnetic material exhibiting different states of remanence intermediate and including a first and a second limiting state, a plurality of windings on said cores, means for energizing said windings during a first interval of time for writing in a binary value and during a second interval of time for reading out said binary value comprising, first means energizing said plurality of windings during said first interval of time for establishing both said cores in intermediate remanence states, said cores in said intermediate remanence states jointly representing said binary value, and second means there-

after energizing said plurality of windings during the second interval of time for establishing both said cores in limiting remanence states to read out said binary value.

20. The circuit as set forth in claim 19, wherein both said cores are established in the same remanence state during the first interval of time.

21. In a circuit, a first and a second magnetic core each made of material exhibiting appreciable remanence, each said core capable of attaining different states of remanence intermediate and including a first and a second limiting state, a plurality of windings inductively associated with each said core, means for energizing the windings of each core during a first, a second and a third interval of time comprising, first means energizing said windings during said first interval of time for establishing said cores in said first limiting state, second means energizing said windings during the second interval of time for writing in a binary bit of information and establishing both said cores in intermediate states of remanence, and third means energizing said windings during the third interval of time for establishing both said cores in a limiting state of remanence whereby the state established in said cores during the second interval of time and thus the binary information represented thereby is read out.

22. In a circuit, a first and a second magnetic core, said cores formed of material exhibiting appreciable remanence, each said core adapted to assume a first, a second and a third stable remanence state, where at least one of the stable states of each core is a state other than a limiting state and another of said states is a limiting state, one of the stable states of said first core and one of the stable states of said second core constituting a first combinatorial state for both cores, another of the stable states of said first core and another of the stable states of said second core constituting a second combinatorial state for both said cores, the remaining stable state of said first core and the remaining stable state of said second core constituting a third combinatorial state for both said cores, winding means coupling said cores, means for energizing said winding means during a first and a second interval of time, said last means energizing

said winding means during the first interval of time for establishing said cores in either said first or second combinatorial state to represent a binary value and said last means energizing said winding means during the second interval of time for establishing said cores in the third combinatorial state to read out said binary value.

23. The circuit as set forth in claim 22, wherein the first and second stable states of both said cores are opposite limiting states of flux remanence.

24. In a circuit, a first and a second magnetic core, said cores formed of material exhibiting appreciable remanence, each said core adapted to assume a first, a second and a third stable remanence state, where at least one of the stable states of each said core is a state other than a limiting state and another of said states is a limiting state, one of the stable states of said first core and one of the stable states of said second core constituting a first combinatorial state for both cores, another of the stable states of said first core and another of the stable states of said second core constituting a second combinatorial state for both said cores, the remaining stable state of said first core and the remaining stable state of said second core constituting a third combinatorial state for both said cores, winding means coupling said cores, means for energizing said winding means during a first, a second and a third interval of time; said last means energizing said winding means during said first interval of time for establishing said cores in the first combinatorial state, said last means energizing said winding means during the second interval of time for establishing said cores in the second combinatorial state whereby the joint states of said cores represent a binary value, and said last means energizing said winding means during the third interval of time for establishing said cores in the third combinatorial state to thereby read out said binary value.
